UNITED STATES PATENT OFFICE.

PHILIPPE BOISVERT, OF EAST ANGUS, QUEBEC, CANADA.

TOOL-CHEST HANDLE.

1,112,517.

Specification of Letters Patent.

Patented Oct. 6, 1914.

Application filed April 4, 1914. Serial No. 829,533.

To all whom it may concern:

Be it known that I, PHILIPPE BOISVERT, a subject of the King of Great Britain, residing at East Angus, Province of Quebec, 5 Canada, have invented certain new and useful Improvements in Tool-Chest Handles; and I do hereby declare that the following is a full, clear, and exact description of the invention, such as will enable others skilled 10 in the art to which it appertains to make and use the same.

The invention to be hereinafter described relates to tool chest handles.

In order to more clearly disclose the construction, operation, and use of the invention, reference should be had to the accompanying drawings forming part of the present application.

Throughout the several figures of the 20 drawings like reference characters designate the same parts.

In the drawings: Figure 1 is a perspective view of a tool chest with the invention applied; Fig. 2 is an enlarged side elevation 25 of the invention; Fig. 3 is a section on line 3—3 of Fig. 2 looking down; Fig. 4 is an enlarged detail of one handle in operative position; and Fig. 5 is a detail back view of the sleeve for holding the handles 30 in inoperative position.

The main objects of the invention are, to provide a simple, efficient, durable, economical, and compact handle which may be easily and quickly slid to and from operative position, and one which will always accompany the chest and be convenient and accessible to be drawn to operative position at any time.

Referring to the drawings in detail, 1 indicates brackets provided with longitudinal 40 bores. These are secured in sets of three to the upper part of each of the longer sides of the chest, and receive longitudinal guide and brace rods 2 which extend the entire 45 length of the chest. Each rod is in two sections which have their inner ends threaded into the opposite faces of a block 2^a secured in the center of a sleeve 2^b carried by the center bracket 1, by means of a set screw 3, 50 which passes through the bracket and the sleeve as well, for securing purposes, as shown in Fig. 2. By removing set screw 3 and unscrewing each of the rod sections from block 2^a the handle may be quickly and 55 easily taken apart for shipping. The ends of each rod are loose in the end brackets the

bores of which are of larger diameter than and concentric with the rod. Within the bores and slidable on each end of the rods are sleeves 4 with removable screw threaded 60 end knobs 5 and limiting lugs 6. Each sleeve, preferably, extends the full length of the distance between the center and one end bracket, and the lugs 6 are placed about midway of the length of the sleeves. Thus, 65 when the sleeves are drawn out to their greatest distance, one half of their lengths incloses and is braced by an equal section of the rods. This, of course, counteracts the strain on that part of each of the handles 70 which has been slid outwardly or about the rod.

In order to hold the sleeves in their inoperative positions, leaf springs 7 integral with sleeve 2^b, are provided. These springs are 75 formed by providing two parallel slits in the sleeve 2^b, a slight distance apart, extending from each face of block 2^a to each end of the sleeve. The tongues of metal thus formed are bent inwardly and dished, near 80 their outer ends. This forms a rounded gripping knob, which grips the inner end of the sleeve, by friction, when it is pushed into the sleeve 2^b, and holds it in inoperative 85 position; as clearly shown in Fig. 3.

It is thought that the construction, operation, and use of the invention will be clear from the preceding detailed description.

Changes may be made in the construction, arrangement, and disposition of the several 90 parts of the invention without in any way departing from the field and scope of the same, and it is meant to include all such within this application wherein only a preferred form has been disclosed.

Having thus fully described my invention, what I claim as new and desire to secure by Letters Patent is:

1. In combination, a plurality of brackets, a rod fixed to one of said brackets and having its opposite ends extending concentrically through the remaining brackets, sleeves 100 slidably mounted on the free ends of said rod and movable through said brackets, stop lugs extending from said sleeves and adapted to engage said brackets, and leaf springs adapted to engage said sleeves and 105 yieldingly retain them in inoperative position.

2. In combination; a plurality of brackets; a sleeve carried by the center bracket of 110 each set and secured therein; a block centrally secured in the said sleeve; a rod con-

sisting of two parts threaded into the opposite faces of the said block, and having its ends extending freely and concentrically through the bores of the remaining brackets 5 of the set; sleeves slideable on the said rods and movable through the said brackets; a stop lug projecting from each sleeve midway of its length and adapted to engage a bracket, as the sleeve is slid outwardly; and 10 leaf springs integral with the first men-

tioned sleeve and adapted to yieldingly engage the last mentioned sleeves, so as to hold them in inoperative position.

In witness whereof I have hereunto set my hand in the presence of two witnesses.

PHILIPPE BOISVERT.
